UNITED STATES PATENT OFFICE.

JAMES EDWARD HILLS, OF NEW YORK, N. Y.

DESIGN FOR A PATTERN-SHEET FOR ADVERTISING TOOTHPICKS.

SPECIFICATION forming part of Design No. 35,376, dated December 3, 1901.

Application filed November 8, 1901. Serial No. 81,628. Term of patent 14 years.

To all whom it may concern:

Be it known that I, JAMES EDWARD HILLS, a citizen of the United States, residing at New York city, in the county of New York and State 5 of New York, have invented and produced a new and original Design for a Pattern-Sheet for Advertising Toothpicks; and I do declare the following to be a full, clear, and exact description of the same, reference being had to the accompanying drawing, forming a part thereof.

The figure of the drawing is a plan view of a pattern-sheet, showing my new design.

As shown in said drawing, the design con-

sists of a sheet of material embodying a series 15 of advertising toothpick-blanks, comprising various contours—such as rectangular and oval figures, bottles, shoes, banners, and similar articles—grouped as illustrated.

Having described my invention, what I 20 claim as new, and desire to secure by Letters Patent, is—

The design for a pattern-sheet for advertising toothpicks, as herein shown and described.

JAMES EDWARD HILLS.
